United States Patent Office

Des. 198,215
Patented May 19, 1964

198,215

STATUETTE

Justin Sturm, Sylvan Road, Westport, Conn.

Filed Mar. 27, 1963, Ser. No. 74,151

Term of patent 14 years

(Cl. D29—23)

Fig. 1

Fig. 2

FIG. 1 is a front perspective view of a statuette showing my new design.

FIG. 2 is a rear perspective view thereof.

I claim:

The ornamental design for a statuette, substantially as shown.
